UNITED STATES PATENT OFFICE.

WILLIAM H. PRICKETT AND JAMES F. MORTON, OF TRENTON, NEW JERSEY.

SHADE-HOLDER FOR ELECTRIC LAMPS.

Specification of Letters Patent.

Patented May 6, 1919.

1,303,112.

Application filed September 14, 1918. Serial No. 254,127.

To all whom it may concern:

Be it known that we, WILLIAM H. PRICKETT and JAMES F. MORTON, citizens of the United States, and residents of Trenton, in the county of Mercer and State of New Jersey, have invented a new and Improved Shade-Holder for Electric Lamps, of which the following is a full, clear, and exact description.

10 This invention relates to shade holders especially adapted for use in connection with an ordinary incandescent lamp socket.

The invention has for its general objects to improve the construction of shade holders 15 so as to perfect diffusion of light, prevent dust and insects from entering the globe, and at the same time providing for the free circulation of air around the lamp, the shade holder being of comparatively simple and 20 inexpensive construction, reliable and efficient in use, and so designed that it can be adapted for lamp sockets and shades of ordinary form.

A more specific object of the invention is 25 the provision of a shade holder having screened ventilating apertures in combination with a protector which encircles the lamp socket and rests on the shade holder in spaced relation thereto, whereby rain and 30 dust are prevented from entering the shade, although free space is provided for the circulation of air through the apertures of the shade holder.

With such and other objects in view, the 35 invention comprises various novel features of construction and arrangement of parts which will be set forth with particularity in the following description and claims appended hereto.

40 In the accompanying drawing, which illustrates one embodiment of the invention and wherein similar characters of reference indicate corresponding parts in both the views,

45 Figure 1 is a central vertical section of the shade holder; and

Fig. 2 is a plan view with a portion of the protecting ring or cap-piece broken away.

50 Referring to the drawing, A designates an ordinary lamp socket, B the shade holder and C the shade.

The shade holder B comprises a sheet metal stamping in the form of a crowned plate 1 having a central opening 2 at which 55 is provided a depending screw flange 3, and

at the periphery is a depending flange 4 having lugs 5 that carry screws 6 which clamp the globe C to the shade holder. On the under side of the shade holder is a 60 screen 7 which is a piece of wire mesh of such diameter as to fit within the flange 4, and this wire gauze has a central opening 8 of such size that the screen can be forced on the flange 3 and frictionally remain 65 thereon. The shade holder is attached to the socket 2 by means of a threaded sleeve 9 which, together with the shade holder, are common articles of manufacture.

In order to prevent dust and the elements 70 from entering the shade a protector D is employed. This is in the form of a sheet metal cap or ring 10 which is arched or dished and provided with a central opening large enough to slip over the sleeve 9, there 75 being a downwardly extending flange 11 at the opening, the edge of the flange being adapted to bear on the top surface of the shade holder, whereby the protector is supported in spaced relation from the shade 80 holder in order to permit of the free circulation of air through the shade. This protector D also serves to prevent direct light rays from passing out from the lamp, so that a uniform diffusion of light is rendered 85 possible.

The points of merit in the present invention are the perfect diffusion of light, dust and insect-proofness, ample ventilation for 90 the lamp, and simplicity and economy of cost, the invention being a device that can be readily installed without any electrician, and placements made upon drops, cords or chains already in use.

From the foregoing description taken in 95 connection with the accompanying drawing, the advantages of the construction and method of operation will be readily understood by those skilled in the art to which the invention appertains, and while we have 100 described the principle of operation, together with the device which we now consider to be the best embodiment thereof, we desire to have it understood that the device shown is merely illustrative and that such changes may be made when desired as fall 105 within the scope of the appended claims.

Having thus described our invention, we claim as new and desire to secure by Letters Patent:

1. The combination of a lamp socket, a shade holder thereon having ventilating

- apertures, means to secure said holder to the socket, and a device surrounding the socket and having means to support the same on said holder independently of the fastening of the holder to the socket, and serving to position said device over and spaced from the apertures of the shade holder, to prevent dust or rain passing through the apertures while permitting a free circulation of air.
- 10 2. The combination of a lamp socket, a shade holder attached thereto and having ventilating apertures, an arched member surrounding the lamp socket and having a central aperture formed with a depending flange engaging the top surface of the holder, whereby the member extends over the apertures of the shade holder and permits of a free circulation of air through the apertures.
- 15 3. A shade holder comprising a member having a central opening and ventilating apertures between the opening and periphery of the member, means for attaching the holder to a lamp socket depending within the holder, and a screen having an aperture, 25 the edges of which have a forced engagement with the said depending attaching means, whereby the screen is held fixed with respect to the apertures of the said member.
4. The combination of a lamp socket, a 30 shade holder thereon and having ventilating apertures, means fastening said holder to the socket and presenting a neck above said holder and an annular cap-like protecting device loosely disposed around the lamp 35 socket, the device having a central opening to snugly receive said neck and having a depending flange at said opening for supporting said device in raised relation to the shade holder to cover the ventilating apertures thereof while permitting the free circulation of air through the apertures.

WILLIAM H. PRICKETT.
JAMES F. MORTON.
